Des. 228,841
Patented Oct. 30, 1973

228,841

BASE FOR BATHROOM FIXTURE AND THE LIKE

Willard H. Sahloff, Bridgeport, Conn., assignor to Handy-Andy Specialty Co., Inc., New York, N.Y.

Filed Aug. 27, 1971, Ser. No. 175,810

Term of patent 14 years

Int. Cl. D6—06; D8—08
U.S. Cl. D6—86

FIG. 1 is a top plan view of a base for bathroom fixture and the like showing my new design;

FIG. 2 is a side elevational view thereof; and

FIG. 3 is a bottom plan view thereof.

I claim:

The ornamental design for a base for bathroom fixture and the like, as shown.
